COMPARTMENTED PILLOW

Randall M. Sourbeck, Akron, Ohio, assignor to
 Interstate Latex Company, Youngstown, Ohio,
 a corporation of Ohio

Application August 5, 1946, Serial No. 688,492

3 Claims. (Cl. 5—341)

1

This invention relates to pillows, cushions, and equivalent stuffed casings, and in general has reference to a novel cellular construction which assists in maintaining the filling properly allocated to insure substantially uniform comfort when the article is in use.

Various types of pillows, cushions or the like have heretofore been made either with or without internal dividing partitions. Those without dividers or partitions with fillers of feathers, down, latex foam rubber or other materials tend to lose their shape when pressure is applied at any one point and must be fluffed or shaken to bring them back to a semblance of their original shape. Usually those made with dividers or partitions are constructed so that the ends of the compartment formed between the dividers are not adequately sealed and the filling material can shift from one compartment to another and eventually cause an uneven distribution of the filling material resulting in lumps or a distorted unit.

A principal object of the invention is to provide a pillow with novel compartmentation which is strong and durable, whereby shifting of the filling material from one compartment or cell to another is eliminated, and the said filling material is adequately confined over long periods of use.

Another object is to provide a novel method of making a compartment type pillow and filling the same in a manner to insure that the article will retain its original thickness within close limits with any type of filling material.

A further object is to provide a pillow, cushion, casing or the like, having desirable sanitary characteristics in the respect that it can be washed and dried without removing any of the contents and without changing the original shape. In that connection, this objective is made possible by the use of partitions or dividers, which by the present novel means of sealing or closing the ends of the dividers, assures the permanent positioning of the material in each compartment within the pillow casing.

Other objects and advantages of the present invention will appear from the following description when read in conjunction with the accompanying drawings wherein:

Figure 1 is a perspective view of a pillow casing, for example, showing one end thereof parted for filling prior to sewing the ends closed, but showing the end portions folded preparatory to their interfitting relation.

Figure 2 is a cross section view taken along the line 2—2 of Figure 1.

2

Figure 3 is a top view in elevation of the pillow or casing closed up and ready for use.

Figure 4 is a more or less diagrammatic detail section of the seam formed at each end of the pillow taken on section line 4—4 of Fig. 3.

Similar references designate corresponding parts throughout the several figures of the drawings.

The novel construction herein described is primarily intended for use with such cushioning materials as shredded latex rubber foam, sponge rubber, or any other form of rubber or material of similar texture having inherent resiliency and in effect buoyancy when under pressure, whereby, 10 when a casing or other single receptacle is filled to capacity or near capacity therewith, such materials are not unduly compressed or compacted and have to preserve their initial resiliency and cushioning qualities. Accordingly, to provide for 15 the strain applied to the seams of the pillow, cushion, casing or the like stuffed with such resilient materials, it is proposed to provide a novel method of seaming or hemming the ends of the pillows and compartments so as to effectively resist 20 the strains imposed thereon by the distortion of the resilient fillers when displaced in the respective compartments by compressive stress.

Referring first to Figure 1 and the particular structural features of the seams and partitions. 30 10 designates a casing comprising a flexible sheet of woven fabric, vinyl resin film, rubber hydrochloride and other coated materials, which is turned over, for example, inwardly along each edge thereof to provide a flange or hem 11. 35 After this has been done, dividers or partitions 12 are prepared at the ends with a like flange or hem 14 along their shortest edges. These dividers may be of the same material as the casing if desired.

The partitions 12 are then folded over upon themselves lengthwise, so that the flanges 14 are doubled over to provide a quadruple thickness, and the doubled over flange 14 of one end is inserted under a portion of one flange 11 of the 40 casing or main cover 10. This casing is then folded over upon itself lengthwise, so that the doubled over flange 14 of the partition ends is "sandwiched" in between the now doubled over flange 14 of the casing. Likewise, the longitudinal edges of the partitions are flanged over at 45 (Fig. 2), for sewing to the inner side faces of the casing 10. These flanged over longitudinal edges 15 continue to the end flanges 14 of the partitions 12 and the portions 15 as sewed by stitches to 50 55 the main cover 10.

The doubled over flanges 11 and 14 providing eight thicknesses are now ready to be stitched or sewed together as indicated at S to form an exceptionally strong seal at the end of the pillow and also to seal one end of each compartment defined between each partition. When this has been done, the stitching may be continued along the open side 16 of the casing 10, so that the casing and compartments therein are now sealed or closed completely on three sides. This leaves an end of the casing and the ends of the several compartments open to facilitate filling with the desired stuffing materials.

The filler material may be dispensed from a hopper or other suitable device in predetermined measured quantities according to the volumes of the several compartments. For example, the two outside compartments are somewhat smaller than the interior compartments, due to the fact that the outside edges of the casing, pillow or the like are more or less rounded. Accordingly, a smaller amount of filler, such as shredded latex, for example, is placed in the outside compartments than in the larger intermediate compartments.

After the compartments have all been filled according to their respective capacities, the unclosed open end 17 of the casing 10 and the partition ends with their respective flanges are interfitted and hemmed together in the same way as was the other end thereof. Thus, after the casing 10 is closed on all sides as described, the contents of each compartment is absolutely separated from the contents of the adjoining compartment. As the partition ends are folded over at flange 14, the partitions are caused to twist out from each end of the pillow and tend to straighten out at the mid sections 18 thereof from the pinched together flanged end portions when the compartments are stuffed. The fact that the filler cannot shift from one pocket to another serves to maintain a casing, pillow, or the like, of substantially uniform shape and thickness.

While the drawing shows the partitions longitudinally of the casing 10, it is to be understood that they may, if desired, be arranged across the casing or at various angles or combinations thereof. Also, the partitions may be made of varying sizes, for example, from four inches wide and six inches long to five feet wide and six feet, six inches long. When a pillow is thus made, it is very useful and desirable for hospitals, hotels and institutions where pillows, cushions or filled casings become soiled or exposed to contagious diseases and must be sterilized before they can be used again, as the whole unit may be conveniently sterilized without fear of ruining its shape, appearance, or usefulness.

Without further description, it is thought that the novel features of the present invention will be readily understood by those skilled in the art and it will, of course, be understood that changes may be resorted to within the scope of the appended claims.

I claim:

1. A pillow or the like, including, a sheet folded over to form a casing having oppositely positioned sides with turned over edges, a plurality of partitions in said casing, filling material between each partition, each partition at each end having a turned over end flange, each of said flanges being folded over upon itself to form a double thickness of each partition end, each doubled

over flanged partition end being inserted under one of the turned over edges at each end of the casing and hemmed to the said edges of the casing to form seams, and said partitions being spaced apart and sewed along their respective longitudinal edges between the flanged partition ends to the opposite inner faces of the said sides of the casing, thereby to form a plurality of compartments adapted to separately confine said filling material.

2. A pillow or the like, including a flexible sheet folded in half to form a casing having top and bottom sides, a plurality of divider strips spaced apart and sewed to the inner faces of said sides, each of said strips being turned over to form a flanged edge along each end, each of said flanged edges being folded over to form a double thickness and hemmed between the edges of the folded casing sheet at each end of the pillow to thereby close the ends of the casing and define a plurality of closed compartments in the casing between said strips, said compartments being stuffed with resilient material, such as shredded rubber.

3. The method of making pillows or the like comprising the following steps: turning over the edges of a piece of flexible sheet material, folding the sheet in half to provide oppositely facing top and bottom sides of a pillow with the turned over edges of the top side superimposed above the corresponding turned over edges of the bottom side of the pillow along three edges thereof, two of said edges at each end being end edges and two of said edges on one side being side edges, then sewing each of the opposite longitudinal edges of each of one of a plurality of elongated partitions of sheet material between the said sides in spaced apart relation, then sewing under one of the turned over end edges of one of the said sides of the sheet material the doubled over transverse end of each one of said spaced apart partitions to form a seam along one end of the pillow, then sewing the opposite turned over end edges of the sheet material together to thereby form a closed end, then sewing the two superimposed sides edges together, then filling the space between each partition with a predetermined quantity of stuffing material, and then sewing the opposite ends of the doubled over partitions similarly between the oppositely disposed superimposed end edges, so as to close the other end of the pillow.

RANDALL M. SOURBECK.
